(57) **CLAIM**

The ornamental design for a cup lid, as shown and described.

DESCRIPTION

FIG. 1 is a top, front, and right side perspective view of a cup lid, showing our new design;

FIG. 2 is a bottom, front, and right side perspective view thereof;

FIG. 3 is a top, rear, and right side perspective view thereof;

FIG. 4 is a front view thereof;

FIG. 5 is a rear view thereof;

FIG. 6 is a top view thereof;

FIG. 7 is a bottom view thereof;

FIG. 8 is a right side view thereof;

FIG. 9 is a left side view thereof; and,

FIG. 10 is a front, right side perspective view of the cup lid in an open configuration.

The broken lines in the drawings depict portions of the cup lid that form no part of the claimed design.

1 Claim, 10 Drawing Sheets
